UNITED STATES PATENT OFFICE.

HIRAM G. SEDGWICK, OF MILL VALLEY, CALIFORNIA, ASSIGNOR TO THE NATIONAL SAFETY APPLIANCE COMPANY, A CORPORATION OF CALIFORNIA.

TRAIN-STOP AND SIGNALING SYSTEM.

1,225,508.

Specification of Letters Patent.

Patented May 8, 1917.

Application filed November 23, 1912, Serial No. 733,162. Renewed October 9, 1916. Serial No. 124,683.

To all whom it may concern:

Be it known that I, HIRAM G. SEDGWICK, a citizen of the United States, and a resident of Mill Valley, county of Marin, State of California, have invented certain new and useful Improvements in Train-Stop and Signaling Systems, of which the following is a full and clear specification, reference being had to the accompanying drawings, in which—

Figure 1 is a diagrammatic view of a portion of a steam locomotive showing my invention applied thereto;

Fig. 2 an elevation of a portion of a locomotive truck showing the parts of my apparatus carried thereby, a part of the frame of my apparatus being shown in vertical section and the view being taken looking rearwardly;

Fig. 2^a a rear elevation of the apparatus mounted on the truck and the adjacent parts mounted on the under side of the railway vehicle body.

Fig. 3 a detailed vertical section of the valve box and circuit closer;

Fig. 4 a horizontal sectional view through the top of the armature box;

Fig. 5 a vertical longitudinal sectional view thereof;

Fig. 6 a detail vertical longitudinal section of the armature box showing one of the armatures in the act of opening a vent valve;

Fig. 7 a transverse vertical sectional view of the armature box;

Figs. 8 and 9 detail views showing the manner of supporting the armature-box carrying frame upon one of the axles of the locomotive;

Fig. 10 a vertical sectional view showing a modified form of the valve box and circuit closer;

Fig. 11 an end view of the cylinder shown in Fig. 10; and

Fig. 12 a diagram of a lamp circuit adapted to my present invention.

The object of this invention is to provide simple automatic mechanism on the locomotive or other vehicle which will coöperate with road bed devices to produce in the cab a series of control signals or cause an automatic application of the brakes when the road bed devices are properly set. Several of the features of my invention are adapted especially for coöperation with an electro-

magnet on the road bed through whose magnetic field certain armatures on the vehicle pass as the train moves past the magnet, the movement of the armatures being suitably translated into signals or train stopping action, while certain other parts of the invention are adapted to be used in connection with any type or system of road bed appliances, as more fully hereinafter set forth.

Referring to the drawings by numerals, 65 1 designates a pair of bars attached at their forward ends to the under side of the truck frame of the tender or locomotive and extending rearwardly therefrom, the attaching devices being such as to permit these 70 bars to have a slight pivotal motion up and down. These bars extend rearwardly and are rigidly connected at their rear ends by a cross bar 2. Attached to this cross bar is a yoke-like hanger 3 which surrounds the 75 axle and serves to suspend the rear end of the frame from the axle, suitable anti-friction devices 4 being mounted within the upper part of the yoke and adapted to rest upon the axle. To prevent the frame re- 80 bounding upwardly a stop 5 is attached to the arms of the yoke just below the axle.

Rigidly attached to the bar 2, one at either side of the center of the vehicle, is a pair of shoes 6 each of which has its front as 85 well as rear side beveled upwardly so as to more readily pass over obstacles on the road bed. These shoes depend close to the road bed and are provided with a box or frame 7 whose top side is closed but whose bottom 90 side is open. This box is set up into the shoe so as to be guarded by the beveled or runner-like forward and rearward projections of the shoe. In each shoe is arranged a series of four armatures 8, these armatures 95 being normally drawn up into the box by means of springs 9. Each armature is preferably T-shaped in cross section, the web portion extending up between the series of separated horizontal bars 10 rigidly mounted 100 within the box. The flanges at the lower edge of each armature serve as stops to prevent the spring drawing the armature up beyond the bars 10. The springs 9 are inclined forwardly so as to tend not only to 105 draw the armature up but to pull them forwardly against the forward sides of the box.

The bars 10 are so located that when the armatures are drawn up against their under sides, they will be bodily above the lower 110

edge of the box, so as to be out of the way of injury by contact with obstacles on the road bed. The box 7 is preferably of some non-magnetic material. At the rear end of each 5 armature it is provided with a nose-piece 11 at its lower edge which is virtually an extension of the flanges at the lower edge of the armature. Fastened to the rear wall of the box is a series of vent valves 12, the stems of 10 whose valves normally project into the box, this normal position of the valves being caused by fluid pressure conveyed to the valves by a series of independent pipes 13. There is one of these valves for each of the 15 armatures and each of the pipes 13 extends upwardly and is connected with mechanism hereinafter described whereby when the vent valve 12 is opened air will be exhausted from its connecting pipe 13 and thus cause a signal 20 or a train stopping device on the locomotive to be put into action, as more fully hereinafter set forth. It will be observed that when one of the armatures passes through the magnetic field of a road bed 25 magnet, the armature will be pulled down out of the box against the action of its spring 9 far enough to bring its nose 11 below the lower edge of the box, whereupon the drag on the armature will forcibly throw 30 it backwardly and cause the end of the armature to strike the stem of the vent valve, and thus force the same to an open position, thus venting its pipe 13. After the armature is passed beyond the influence of the 35 road bed magnet its inclined spring 9 will promptly pull it forwardly and upwardly and thus return it to its normal position within the box, whereupon the vent valve will again be seated by the pressure from 40 pipe 13.

It will be observed that by arranging the armatures up above the lower edge of the box they are not only protected from obstacles on the road bed but they are prevented 45 from accidentally or prematurely actuating the vent valves, the projections 11 serving to hold the armatures away from the valve stems until they are drawn downwardly out of the box far enough to permit the armatures to move endwise in a direction rearwardly with respect to the movement of the train. It is intended that these armatures will coöperate with a series of road magnets staggered along the road bed, 55 each armature being adapted to coöperate with a magnet located at a certain distance from the center of the road bed and with no other magnet.

It will be understood also that one of the 60 set of armatures is intended to operate with road bed magnets which are arranged to control trains going in one direction only while the other set of armatures is adapted to coöperate with road bed magnets set so 65 as to control trains going in the opposite

direction, so that each locomotive provided with my invention will be subject to the road bed controlling system whether the locomotive be going forwardly or backwardly. Of course the set of armatures that is on the 70 left hand side of the locomotive will be arranged to operate in a direction reverse to that of the set on the other side of the center of the locomotive. It will be observed that a feature of importance lies in the manner 75 of carrying the armature boxes on a frame which is swung from one of the locomotive axles, whereby great accuracy may be obtained in the matter of arranging the armatures with respect to the poles of the 80 road bed magnets, it being obviously desirable to not only bring the armatures as close as practicable to the poles of the magnets but to also prevent the jarring of the train from moving them out of their predetermined line of travel. As it is well known that the axles of the locomotive have but a 85 very slight vertical movement even on the roughest road bed, it will be seen that by hanging the armature box from one of the 90 axles I secure a high degree of accuracy and 95 steadiness.

One of the pipes 13 from each of the armature groups, preferably the one nearest the center of the vehicle, is connected to a 95 suitable train brake setting valve A, as shown in Fig. 1, so that when the innermost armature of either of the groups is actuated the brakes will be applied by the venting of the train pipe in a well known manner. 100 There will be associated with these brake applying armatures, suitable road bed magnets which will operate with these armatures and no others and as both the train stopping vents are connected to the stopping 105 valve A, the train will be stopped when either one of these armatures is actuated.

The remaining three tubes 13 of each group of armatures are carried upwardly and respectively connect to the ends of two 110 groups of tubular chambers 14, which are closed at their ends and are supported by and extend through an air chest 15, which chest is kept constantly in communication with the main air reservoir 16 by a pipe 17, 115 so that the interior of the chest 15 is at all times under the same pressure as the reservoir. The interior of each tube is in communication with the interior of the chest by openings 18 in the tubes. In each tube is 120 affixed a pair of oppositely facing valve seats 19 and 20 and adapted to alternately seat against these seats is a pair of valves 21 and 22, these valves being connected by a stem 23. The stem is of such length that 125 only one valve at a time can be seated. Both ends of the tubes 14 project beyond the sides of the air chest 15, and at the ends opposite the ends connected to the tubes 13 I mount suitable whistles 24 and signal lamp 130

terminals 25 which are adapted to be closed by a contact block 26, attached to the adjacent valve 21. One of the lamp terminals is grounded and the other is carried up into 5 the locomotive cab.

It will be observed that when one of the tubes 13 is exhausted by the vent valve 12, the air beyond the valve 22 will be exhausted or reduced in pressure, whereupon said 10 valve 22 will be instantly closed. This closing of valve 22 will open valve 21, in view of the fact that valve 22 and the passage that it controls are larger than the valve 21 and its passage, this difference in area causing a 15 differential pressure on the valves in favor of valve 22. The opening of valve 21 will not only permit air to escape into the whistle end of the tube and thus sound the whistle but will cause the contact block 26 to 20 close the circuit between the lamp terminals 25 and thus light that one of the lamps in the cab which is associated with the particular lamp terminals which have been connected. It is intended that each one of the 25 tubes 14 shall be provided with a whistle and that the whistles of each group shall be so constructed as to give different sounds. The lamps in the locomotive cab will be different in color to indicate the different signals, safety, caution and danger. 30

After one of the signal devices has been thus operated, the parts may be restored to normal by pushing the valve 22 away from its seat far enough to seat the valve 21, this 35 being desirably done by letting air into the ends of the tubes 14 from the main reservoir 16 to thus bring the pressure in the end of the tube to an equilibrium with the pressure inside of the valve 22. To thus convey a 40 pressure from the reservoir 16 I connect up each of the cylinders 14 with the reservoir by means of pipes 27 and place therein a small valve 28 which the engineer may open whenever he desires to restore the valves to 45 normal.

The signal lamps 29 are arranged in the cab in two groups of three each, one group being arranged at the forward part of the cab and the other being arranged at the rear 50 part of the cab so that no matter in which direction the locomotive is moving the engineer will face one set or the other of these signal lamps. One set of lamps is connected up with one group of terminals 25 and the 55 other set of lamps is connected up to the other group of terminals, so that when the engine is running forward the front set of lamps will be subject to actuation, this front group being connected up through the appropriate set of terminals 25 with the group 60 of corresponding armatures at the right hand side of the vehicle; the other or rear group of lamps is connected up to the other set of terminals and is therefore subject to 65 actuation only by the armatures on the left

hand side of the locomotive, these armatures being in such position that they can only be actuated when the locomotive is backing, in which event the engineer will be facing said rear set of lamps. This double set of signal 70 lamps is a very important feature of my invention since it keeps the appropriate set of signals immediately in front of the engineer no matter in which direction the locomotive may be traveling, thus enabling the engineer 75 to see the signals without taking his eyes off the track ahead.

Any suitable lamp wiring may be employed as is evident, one simple arrangement being illustrated diagrammatically in Fig. 12. It will be observed also that many changes in the details of construction may be made without departing from my invention. I illustrate in Fig. 10 one modification of the valve device for pneumatically closing the lamp circuits and sounding an audible signal. This modification embodies a cylinder 30 which is bolted against one side of the air chest 15 and has its outer end connected by a port 31 with the vent pipe 13, this port extending, for convenience, through a tube 32 connecting the walls of the chest 15. A piston 33 works in the cylinder 30, and from one side of this piston projects a stem 34 whose outer end is attached to a smaller piston 35 which works in a cylinder 36 partly closing the end of the cylinder 30. When piston 35 is at the outer extremity of its stroke it closes the lamp circuit between the two terminals 25 affixed to the end of the said cylinder 36. 85

Projecting from the opposite side of the piston 33 is a rod or stem 37 larger in area than the rod 34, and this rod 37 has its other end connected to a piston 38, which latter piston works in the forward end of cylinder 30, which part of the cylinder is of smaller bore so as to fit this smaller piston. Any air that may accumulate between the piston 38 and the air chest 15 may escape 110 through the lateral ports 39. Cylinder ports 40 and 41 open into cylinder 30 on opposite sides of the piston 33 when the same is in normal position (which position is shown in Fig. 10), and these two ports 40 and 41 are 115 connected by a common port 42 to the interior of the air chest 15. When the piston 33 is in its normal position it closes the whistle port 43, which like port 31 extends through the air chest. The piston 33 is held 120 in its normal position by reason of a differential pressure on its opposite sides, the predominance of pressure being on the outer side, that is, the side connected to stem 34. The instant the pressure is reduced in front 125 of piston 33 by the venting of port 31, the predominance of pressure shifts to the inner side of the piston and this causes the piston to quickly move at least far enough to cover port 40 and to uncover port 43, whereupon 130

the whistle will be sounded and the pressure behind the piston 33 will cause it to move more or less slowly far enough to close the circuit between contacts 25. The speed of 5 movement of the piston 33 can be governed to a nicety by properly proportioning the various ports, as is obvious. To restore the piston 33 and its attached parts to normal it is simply necessary to push in the piston 10 35, which may be done in any suitable manner but is preferably done by means of a suitable fluid pressure ram, a part of which is shown in dotted lines in Fig. 10, at 35', and which may be operated from the air reservoir or by steam from the locomotive boiler 15 or in any other manner.

Having thus described my invention, what I claim as new and desire to secure by Letters Patent, is—

20 1. In combination with a railway vehicle, two sets of armatures carried thereby, one set being arranged at each side of the center of the vehicle, two groups of train control devices, means operated by one set of armatures while the train is going in one direction to actuate the devices of one group and means operated by the other set when the train is going in the opposite direction to actuate the devices of the other group and 25 means to operate each armature independently of all the other armatures.

2. In combination with a railway vehicle, train control devices thereon embodying a non-magnetic armature box having its lower 30 side open, an armature and means for normally drawing it upwardly and forwardly into the box, a positive abutment being provided at the rear end of the armature for preventing it actuating the train control devices while in normal position, and means 35 whereby the armature will actuate the train control devices when it is drawn downwardly and rearwardly out of abutting relation.

40 3. In combination with a railway vehicle, train control devices thereon, an armature box horizontally supported, a series of separated horizontal bars in said box, a series of bar armatures flanged at their lower edges 45 and having their web portions extending up between said bars, springs for normally drawing these armatures upwardly, and means whereby when each armature is pulled downwardly against the action of its spring 50 it will cause an independent actuation of one of the train control devices.

45 4. In combination with a railway vehicle,

two sets of visual signals, one set being mounted forward of the engineer's usual position in the vehicle and the other set being 60 located at the rear thereof, and constantly operable means for actuating the forward set when the vehicle is moving forwardly and the rear set when the vehicle is moving rearwardly said means embodying devices 65 whereby each set operates wholly independent of the devices for actuating the other set.

5. In combination with a railway vehicle, two sets of visual signals, one set being in front of the engineer's position and the other 70 set being at the rear thereof, and means on the vehicle adapted to coöperate with road bed devices whereby either set of signals will be actuated according to the direction of movement of the vehicle, said means being 75 constantly operable.

6. In combination with a railway vehicle, a series of signal lamps and circuits therefor, an independent fluid pressure circuit closer for each lamp circuit, and devices 80 adapted to coöperate with the road bed actuating means for independently actuating said circuit closers, and manually controllable fluid pressure means for restoring said circuit closers to normal or inactive 85 positions.

7. In combination with a railway vehicle, a series of visual signals in the cab of the vehicle, a series of fluid pressure differentially operated devices for independently 90 actuating said signals said devices embodying means for normally holding them inoperative, venting tubes connected thereto, and an independent device for venting each 95 of said tubes, these independent devices being arranged to coöperate with road bed devices.

8. In combination with a railway vehicle, a series of signal lamps and circuits therefor, an independent fluid-pressure circuit-closer 100 for each lamp circuit, a common source of fluid pressure for all said circuit closers, and a series of independent venting devices for 105 said circuit closers, the circuit closers being normally held out of action by fluid pressure whereby the venting of any one of them will cause it to close its circuit.

In testimony whereof I hereunto affix my signature in the presence of two witnesses.

HIRAM G. SEDGWICK.
